UNITED STATES PATENT OFFICE.

AMES M. MILLER, OF WASHINGTON, DISTRICT OF COLUMBIA.

INCLOSED CORE FOR TIRES.

1,052,422.

Specification of Letters Patent.

Patented Feb. 4, 1913.

Application filed February 29, 1912. Serial No. 680,725.

To all whom it may concern:

Be it known that I, JAMES M. MILLER, a citizen of the United States, residing at Washington, District of Columbia, have invented certain new and useful Improvements in Inclosed Cores for Tires, of which the following is a specification.

The invention relates to an improvement in inclosed cores for tires of that type including a separable inner section and an outer casing, and is more particularly directed to the inner section which is constructed to provide a full necessary resiliency without the necessity of inflation.

15 The main object of the present invention is the provision of an inner tire section adapted for coöperation with and for ready insertion in and removable from any usual type of outer casing and said inner section 20 being of a non-inflatable type and constructed to provide open air chambers and resilient brace walls.

25 A further object of the invention is the provision of an inner section including a radially disposed and transverse brace wall connected by longitudinal centrally disposed struts, said brace walls being of gradually increasing thickness from their free ends toward their central point, whereby to provide 30 the maximum thickness of material at the main point of strain.

35 A further object of the invention is the provision of a tire in which the space between the brace walls on opposite sides of the central strut provides air cells which when the section is in place on the outer casing forms a series of air chambers for adding to the resiliency of the tire.

40 A further object of the invention is the constructing of a juncture between the struts and brace walls in a manner to avoid an angular relation of adjacent surfaces, or in other words to provide such juncture on the full regular curve from the surface of the 45 brace walls to the adjacent surface of the struts, whereby to avoid the tendency to a breakage or cracking of the material under the strain, incident to the use of the tire.

50 A further object of the invention is the provision of an auxiliary strip preferably a non-conductor of heat in order to avoid the heating of the inner section incident to the friction in use, said strip being secured in place in a simple convenient manner to prevent wrinkling, and the securing means being further utilized as an abutment for the

ends of the section to prevent creeping of the latter when in place.

The invention in the preferred details of construction will be described in the following specification, reference being had particularly to the accompanying drawings in which:

Figure 1 is a broken perspective view illustrating the improved tire construction. 65 Fig. 2 is a transverse section through the inner casing, the non-conducting strip being shown in place, the section being taken on the line 2—2 of Fig. 3. Fig. 3 is a broken horizontal sectional view on the line 3—3 70 of Fig. 2. Fig. 4 is a view in elevation partly in section of the inner section illustrating particularly the means for securing the non-conducting strip in place and for preventing creeping of the inner section. 75 Fig. 5 is a section on line 5—5 of Fig. 4. Fig. 6 is a broken elevation of the inner section showing a slightly modified construction.

Referring particularly to the accompanying drawings, wherein like reference numerals give like parts throughout the improved inner section 1 comprises a resilient non-inflatable link of suitable material, as rubber or the like, and normally of a size to fit snugly within any usual or preferred type or outer casing 2.

The inner section 1 is in effect a solid section formed at suitable and appropriate intervals throughout its circumferential 90 length and on opposite sides of a central longitudinal line with openings 3 which may be hereinafter termed the air cells. These openings are formed in the casing of the section or by other appropriate operation 95 and are so disposed and of such size as to leave between each of said openings in longitudinal alinement what may be termed a brace wall 4, between each pair of openings in transverse alinement what may be termed 100 the longitudinal strut 5. Thus constructed the inner section presents a longitudinal strut 5 extending throughout the length of the section and a series of brace walls 4 extending from such struts at right angles 105 thereto and radially of the section when in tire form relation.

With reference to Fig. 3 it will be noted that each brace wall has its minimum width at its free or outer end and from such point 110 is gradually increased in thickness toward the strut 5, until at its juncture with such

strut there is provided the maximum thickness of material. Therefore on the central longitudinal line 6 there is provided a solid resisting pillar of materially greater thickness than the solid portions of said section beyond such point, whereby the section is materially reinforced at its point of greatest strain.

Another and material point in the construction of sections of this type is provided for in the present improvement in that sharp corners or angular relations of adjacent interior surfaces is avoided. This is particularly plain in Figs. 2 and 3 of the drawings wherein it will be noted that the juncture of each bridge wall with the adjacent strut presents a round surface as at 7, while the juncture of the bridge walls and strut with the upper or relatively outer rim portion 8 of the section is also rounded as at 9. Therefore in the strain incident of the compression of the section in the use of the tire there is a uniform yielding and bending of the material and the tendency to fracture, otherwise incident to sharp corners the angularly disposed adjacent surface is entirely avoided.

The openings 3 are preferably of oval configuration having a length on their major axis somewhat greater than the similar dimension of the section and are preferably offset from the central line of the section so that the inner edge of the opening is nearer the proximate edge of the section than is the outer wall of the opening to the outer edge of the section. This provides a thick outer rim or tread portion 8 of the section and a comparatively thin inner or felly portion 10.

In order to avoid the heating of the section and the friction of the outer casing in use I prefer to provide a non-conducting strip 11, preferably of silk cut bias to enable it to conform to the section. This strip is practically coextensive with the outer surface of the rim or tread portion 8 of the section, and is designed to snugly fit between said surface and the inner surface of the casing 2.

It is of course understood that the improved inner section is in the form of a strip and is to be inserted in the tire by an endwise movement, and under these conditions means must be provided for clamping the non-conducting strip in place and for preventing endwise movement of the section in the outer casing. Such means is illustrated more particularly in Figs. 4 and 5 and comprises a threaded bolt 12 designed to be passed through the felly 13 and rim 14 of the wheel this bolt for the greater portion of its length being split to provide sections 15 and 16. At the inner end the terminals of the sections 15 and 16 are formed to provide creeping plates 17 preferably of fan

shape and formed in any appropriate way to securely grip the non-conducting material. For example, the terminals of the sections may be inwardly turned and formed to provide spurs, and the proximate surface 70 of such plates may be roughened or otherwise formed. In the use of this securing means the ends of the non-conducting strip 11, after such strip and section have been placed in the tire in the outer casing, are brought down between the ends of the section and passed between the creeping plates 17. After the outer casing is secured in place in the ring 14, the bolt having been passed in the usual opening in the rim 80 a nut 18 is tightened on the bolt to draw the non-conducting strip snugly and smoothly in place, as will be apparent from Fig. 4. When in place, as shown in Fig. 4 it will be noted that the wing plates serve as an abutment and prevent endwise movement of the inner section in the casing.

If desired the clamping nut 19 may be arranged on the bolt 12 between the abutting ends of the inner section to more effectively insure a clamping co-operation of the wings on the non-conducting strip, in which construction it will be understood that the nut 19 is tightened to clamp the parts prior to the insertion of the bolt 12 95 through the opening in the felly.

In Fig. 6 I have illustrated a slightly modified form designed to provide for convenient assembling of the section in tire forming relation where an extremely long 100 straight length is used. In order to adapt such straight length for convenient and regular bending into circular form I cut the inner rim portion 10 of the section on radial lines as at 20 cutting from the tire 105 inverted V shaped portions to permit the convenient bending of the length into circular form without undue strain or compression on any part.

In all the forms of the tire section shown 110 it is to be noted that I provide a non-inflatable inner tube that is arranged on the inside of any usual or preferred type of outer casing, one that does not in any way require inflation or other attention to provide the desired resiliency and one which by reason of such advantage is certainly free of liability of punctures, blowouts, or similar troubles which are incident to the usual, inflatable inner tube, and as there is no internal pressure on the outer tire casing, due to inflation, causing blowouts, the durability of the outer tire casing is prolonged until actually worn down by traction alone. Furthermore the formation of the brace 115 walls gives the maximum strength and the size desired; the rounded contours of meeting points of surfaces subjected to strain prevents breakage or rupture; and the use of the non-conducting strip materially in- 120 125 130

creases the life of the section by preventing heat thereof.

Having thus described my invention, what I claim is:

- 5 1. A detachable and non-inflatable inner tire section comprising a length of material formed with central longitudinal web and with openings extending from the sides to but not through said web, a portion of the
- 10 material of the section being cut away in line with the major axis of each opening and extending from the upper end of the opening to and through the bottom edge of the section to permit the bending of the section into circular form while preserving the normal contour of the openings and central web.
- 15 2. An inner tire section comprising an approximately solid length of resilient material formed to provide a series of air-cells therein, the material between said cells providing transverse bridge walls and longitudinal webs, each of said bridge walls having a comparatively narrow marginal
- 20 edge at each side of the section and being of gradually increasing width from each of
- 25

said edges toward the longitudinal center of the section, the webs being of comparatively narrow width and connecting the bridge walls at the points of maximum width of the latter.

3. An inner tire section comprising an approximately solid length of resilient material formed to provide a series of air-cells opening through each side of the section and non-communicating, the cells being divided by transverse bridge walls and connecting webs, said bridge walls being of maximum width on the longitudinal central line of the tire and sharply decreasing therefrom to the free edges of said walls, the webs having a width corresponding to the minimum width of the bridge walls, the adjacent surfaces of the webs and bridge walls merging into each other on curved lines.

In testimony whereof, I affix my signature in presence of two witnesses.

JAMES M. MILLER.
